Primary Examiner — Austin Murphy(74) *Attorney, Agent, or Firm* — Fox Rothschild LLP(57) **CLAIM**

The ornamental design for a single-sided kiosk system, as shown and described.

DESCRIPTION

FIG. 1 is a front perspective view of the single-sided kiosk system showing the new design with two center modular components;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines in the drawings depict portions of the single-sided kiosk system that form no part of the claimed design.

1 Claim, 6 Drawing Sheets(56)
